SLOTTED HOT TOP

Edgar Marburg, Pittsburgh, Pa., assignor to United States Steel Corporation, a corporation of New Jersey

Application January 24, 1957, Serial No. 636,146

12 Claims. (Cl. 22—147)

This invention relates to a slotted hot top and more particularly to a hot top for use in casting hot steel ingots. It has been proposed to use slots in hot tops such as suggested by Turner Patents Nos. 2,049,981 and 2,049,982 and Estep Patent No. 2,159,374. However, the slots shown therein extend completely through the hot top so that if the hot metal flows into the slots it is exposed directly to the air. This will cause the metal to chill rapidly and provide means for conducting heat directly from the top of the ingot. If the metal does not rise in the slots the slots act as chimneys to convey heat directly from the top of the ingot. In either case the extraction of heat from the top of the ingot promotes undesirable trans-solidification across the ingot top.

It is therefore an object of my invention to provide a hot top having slots therein which will serve as an effective barrier to the transfer of heat from the sinkhead through the hot top wall.

This and other objects will be more apparent after referring to the following specification and attached drawings, in which:

Figure 1 is a plan view of a sectional hot top assembled on an ingot mold;

Figure 2 is an enlarged plan view showing the joint between an end and side slab;

Figure 3 is an elevation of the side slab looking toward its inner face;

Figure 4 is an end view of the slab looking toward the left of Figure 3;

Figure 5 is a top plan view of the slab of Figure 3;

Figure 6 is a view, similar to Figure 3, showing the end slab;

Figure 7 is an end view of the slab looking toward the left of Figure 6;

Figure 8 is a top plan view of the slab of Figure 6;

Figure 9 is a view in elevation showing the assembled slabs on a mold section and looking inwardly from the outer side of an end slab;

Figure 10 is a view of a side slab, similar to Figure 3, showing a second modification of my invention;

Figure 11 is an end view of the slab looking toward the left of Figure 10;

Figure 12 is a top plan view of the slab of Figure 10;

Figure 13 is a view, similar to Figure 6, showing a modified end slab which is used with the slab of Figures 10 to 12;

Figure 14 is an end view of the slab looking toward the left of Figure 13; and

Figure 15 is a top plan view of the slab of Figure 13.

Referring more particularly to the drawings, reference numeral 2 indicates the top of a rectangular big-end-up mold. The hot top consists of two refractory side slabs 4 and two refractory end slabs 6. The side slab 4 has a substantially vertical smooth inner face 8 while its outer face has a depressed upper portion 10 and a vertical lower portion 12, which fits the mold wall, whether plain or corrugated. The bottom of the inner face 8 is rounded at 14. A plurality of holes 16 are provided in the wall of

2

the slab 4 for a purpose which will appear later. The tops of the end of the slabs 4 are preferably cut away at 18 so that they are wider at the bottom than at the top. A generally vertical groove 20 is provided in the inner face of slab 4 a short distance from each end thereof. The bottom of the groove 20 tapers downwardly and inwardly at 22 for a purpose which will appear later. The inner side wall 24 of each groove 20 is vertical for the most of its length, but slopes outwardly in a downward direction at its lower end 25 so that the groove is narrower at the bottom than at the top. A generally vertical slot 26 is provided in the upper outer side of slab 4 adjacent each of its ends.

End slab 6 has a generally vertical inner face 28 while its outer face has a depressed portion 30. The contour of the lower portion of the outer face matches the mold wall. The bottom of the inner face 28 is rounded at 31. Each end of the slab 6 has a generally vertical tongue 32 which has tapered sides 34. The width of the upper parallel portion of tongue 32 is less than the width of the upper parallel portion of the groove 20. The lower portion of the tongue 32 has a tapered portion 35 which is of the same slope but slightly closer to its base than tapered portion 22 of slab 4. The inner face of the tongue 32 is tapered at its lower end to provide a wedge surface 32' of the same slope but slightly nearer its base than the tapered portion 25 of slab 4. Portion 36 of the end face is normal to the face 28. Portion 38 of the end face slopes inwardly toward the other end face of slab 6. The height of the tongue 32 adjacent portion 36 is slightly greater than the depth of groove 20 and the height of the opposite side of the tongue 32 is less than the depth of the groove 20. A generally vertical slot 40 similar to slot 26 is provided on the upper outer face of slab 6 adjacent each end.

The parts so described except for minor differences are the same as those shown in my copending application, Serial No. 581,181, filed April 27, 1956. My invention in the present application relates to the addition of a pair of narrow vertical slots 42 in the side slabs 4 and similar slots 44 in the end slabs 6. The width of the slots is preferably not more than $\frac{1}{4}$ inch. The slots are open at their lower end and extend upwardly about two-thirds the height of the hot top or to any height less than that of the hot metal poured into the hot top.

To assemble the hot top on the mold 2, a $\frac{1}{4}$ inch round steel pin 46 is placed in corresponding holes 16 (depending on the height of ingot desired) and the side slabs 4 are placed on opposite sides of the mold 2 with the pins 46 resting on top of the mold as best shown in Figure 9. The end slabs 6 are then inserted between the side slabs 4 with the tongues 32 in the grooves 20. Because groove 20 is wider than tongue 32 in its parallel upper portion, the tongues 32 will pass readily into the grooves 20. When the slab 6 reaches the point where bevelled faces 22 and 35 are in engagement the outer sides of the side slabs 4 are forced towards the mold wall. At the same depth the lower bevels 25 and 32' contact each other, and end slabs 6 are forced outwardly towards the mold wall. With clearances allowed, the slight difference in height of bevelled faces 22 and 35 and corresponding bevels 25 and 32' results in the tops being aligned when a tight fit is secured. When the top of end piece 6 is level with the top of side piece 4, the side face 34 of tongue 32 contacts the outer face 24' of groove 20; hence the end slab 6 cannot drop below the level of the side slab 4. After the four slabs are assembled, a generally U-shaped spring clip 48 is forced downwardly across each joint between the slabs with its legs in the slots 26 and 40.

The above manner of assembly is essentially that shown in my copending patent application. However, as steel is

poured into the mold it cannot rise into the narrow slots 42 and 44 because of the narrow width of these slots and because the slots are not vented. However, air will be entrapped therein and will be heated to a very high temperature, thus serving as an effective barrier to transverse heat flow from the sinkhead through the hot top wall.

Figures 10 to 15 show a second modification of my invention in which the construction and assembly is the same as that of the first embodiment except for the provision of the slots. Therefore, like reference numerals are used to indicate corresponding parts. In this embodiment wide slots 50 are provided in the side slabs 4 and similar slots 52 are provided in the end slabs 6. The width of the slots is preferably at least $\frac{1}{8}$ inch. The slots are open at their lower ends and extend upwardly two-thirds the height of the hot top or to any height less than that of the metal poured into the hot top. Slotted vents 54 extend from the top of the slots 50 to the inner surface of the slab 4. Similar slotted vents 56 extend from the slots 52 to the inner surface of the slab 6. When steel is teemed into the mold it will rise in the slots 50 and then inwardly through the slotted vents 54 to form steel fins which are connected directly to the sinkhead. This prevents the fins from flaring outwardly during rolling. Since the metal fins in the slots 50 and 52 are completely enclosed within the hot top wall the entrapped layer of hot steel will greatly retard heat flow through the walls of the hot top and much less heat will be lost than in the conventional hot top. It will be understood that this arrangement of slots may be incorporated in a one-piece hot top as well as in the sectional hot top described.

While several embodiments of my invention have been shown and described it will be apparent that other adaptations and modifications may be made without departing from the scope of the following claims.

I claim:

1. A hot top for insertion within the walls of a mold comprising a body member having generally vertical inner and outer surfaces and a bottom surface, said body member having a slot extending upwardly from said bottom surface for a distance less than the full height of the hot top.
2. A hot top according to claim 1 in which the slot is relatively narrow and its top is closed.
3. A hot top according to claim 1 in which the slot is relatively wide and there is an opening extending from the top of the slot to the inner side of said body member.
4. A hot top according to claim 1 in which the slot extends upwardly approximately two-thirds the height of the body member.

5. A sectional hot top for insertion within the walls of a mold comprising a first pair of refractory slabs supported on said mold in spaced relationship, a second pair of refractory slabs located between and in abutting relationship with said first pair of slabs, each end of both of the slabs of one of said pair having a generally vertical groove in its abutting face, and a generally vertical portion adjacent each end of both of the slabs of the other of said pair projecting into the corresponding grooves of the other slabs, each of said slabs having a slot extending upwardly from the bottom of the slab for a distance less than the full height thereof.

6. A sectional hot top according to claim 5 in which the slot is relatively narrow and its top closed.

7. A sectional hot top according to claim 5 in which the slot is relatively wide and there is an opening extending from the top of the slot to the inner side of said slab.

8. A sectional hot top according to claim 5 in which the slot extends upwardly approximately two-thirds the height of the slab.

9. A sectional hot top for insertion within the walls of a mold comprising a first pair of refractory slabs supported on said mold in spaced relationship with each other, a second pair of refractory slabs located between and in abutting relationship with said first pair of slabs, and means on said slabs for wedging them against the mold wall, each of said slabs having a slot extending upwardly from within the mold and from the bottom of the slab for a distance less than the full height thereof.

10. A sectional hot top according to claim 9 in which the slot is relatively narrow and its top closed.

11. A sectional hot top according to claim 9 in which the slot is relatively wide and there is an opening extending from the top of the slot to the inner side of said slab.

12. A sectional hot top according to claim 9 in which the slot extends upwardly approximately two-thirds the height of the slab.
